STOP MOTION FOR WRAP STRIPE
MACHINES

William C. Tucker, High Point, N. C., assignor of
one-third to Julia Austin Tucker and one-third
to Sumter Marion Austin, both of High Point,
N. C.

Application February 18, 1952, Serial No. 272,147

13 Claims. (Cl. 66—164)

1

This invention relates to circular knitting machines and more especially to an improved stop motion adapted to be associated with the wrap head of a wrap stripe knitting machine.

This application is a continuation-in-part of my co-pending application entitled Wrap Stripe Stop Motion, Serial Number 188,035, filed October 2, 1950, now Patent No. 2,589,646.

In said co-pending application, an improved stop motion for the wrap head of a knitting machine is disclosed which comprises clamping means in the form of a thread clamp pivotally supported on the table of the wrap head adjacent each of the stobs which support the package or tubes of yarn, and to which the tail of the yarn is clampingly connected. The clamping means is pivoted and has stop means associated therewith being automatically released upon the last few turns of yarn on the corresponding tubes being withdrawn therefrom and which causes the clamping means to be pivoted or elevated by the pull of the yarn. Thus, the stop means is released to engage a suitable mechanism for actuating the conventional stop motion on the knitting machine.

It is the primary object of this invention to provide a stop motion substantially of the character disclosed in said co-pending application but being of lighter construction, having a lesser number of parts and thus being more easily responsive to a very light tension in the tail of yarn as it is withdrawn from the tube and being more economical to manufacture than that of said co-pending application.

More specifically, it is an object of this invention to provide a stop motion actuating device of the character described which is adapted to be secured on the table of a wrap head adjacent each of the tubes of yarn and which may be formed from sheet material, such as sheet metal, wherein a relatively small piece of sheet metal is folded over upon itself at one side thereof to form a tubular portion and is bent upwardly at one end to form a closure tab which closes one end of the tubular portion, this closure tab having a hole therethrough through which the reduced portion of a centrifugally operable plunger extends, the larger portion of the plunger being mounted for free longitudinal sliding movement in the tubular portion radially of the table of the wrap head.

A pivoted arm is also formed from sheet material, such as sheet metal, in substantially the shape of an inverted channel which normally straddles the tubular portion and is pivotally

connected to the tubular portion at a point remote from the closed end of the tubular portion, the pivot pin also serving to limit movement of the plunger inwardly in the tubular portion.

5 The free end of the arm is also bent downwardly to be positioned forwardly of the closed end of the tubular portion to thereby normally prevent the plunger from moving outwardly under the centrifugal force created by rotation of the wrap head.

10 The said arm has a leaf spring member supported thereon by a projection on the outer surface of the arm and this leaf spring member bears against the upper surface of said arm to clampingly hold the tail of yarn from an adjacent bobbin or tube of yarn. Thus, upon the yarn being substantially exhausted from the adjacent tube of yarn, the tail of yarn, as it is pulled upwardly, raises the free end of the said arm to permit the plunger to move outwardly to subsequently contact and actuate an intermediate means to, in turn, actuate the usual stop motion of the knitting machine.

15 Some of the objects of the invention having been stated, other objects will appear as the description proceeds, when taken in connection with the accompanying drawings, in which—

20 Figure 1 is a fragmentary elevation of the upper part of a wrap stripe mechanism of a circular knitting machine with parts omitted and other portions being broken away and showing the improved stop motion actuating means in association therewith;

25 Figure 2 is an enlarged fragmentary top plan view with parts in section looking substantially along line 2—2 in Figure 1;

30 Figure 3 is an enlarged fragmentary vertical sectional view, taken substantially along line 3—3 in Figure 2, showing the stop motion actuating means in inoperative position;

35 Figure 4 is an enlarged elevation, looking substantially along the line 4—4 in Figure 2, showing a portion of the wrap head table in cross-section and showing the stop motion actuating means in an operative position;

40 Figure 5 is a fragmentary view looking at the left-hand side of Figure 3.

45 Referring more specifically to the drawings, the numeral 10 broadly designates a bracket rising upwardly from the body portion of a circular knitting machine, such as the Scott and Williams model HH or model PW machine, and which has a leg portion 11 which supports a platform 13. This bracket 10 supports a conventional 50 wrap stripe attachment generally designated at

14, only fragmentary portions of which are shown in the drawings, since the structure of the usual wrap stripe attachment is well known to those familiar with the art and is fully disclosed in said co-pending application and in such patents as Numbers 1,853,020 and 1,906,204.

The wrap stripe attachment for the wrap head 14 includes a substantially circular lower table 15 and a substantially circular upper table 16 spaced substantially above the lower table 15, 10 which tables are supported and driven to rotate in unison about a vertical axis. The lower table 15 is provided with a plurality of upstanding cone holders, tube holders or stobs 17 which are arranged in a circle adjacent the outer edge of the circular lower table 15. Each of these stobs 17 is provided with a reduced threaded portion 20 on the lower end thereof threadably embedded in the table 15.

The upper table 16 is provided with a plurality of circularly spaced brackets 21 suitably secured around the periphery thereof, only one of which is shown in Figure 1. Each of the brackets 21 has pivotally mounted therein a yarn tension take-up lever 22 having a hook in its free end over which the wrap yarn W is adapted to pass. The outer end of each of the tension levers 22 has a hook portion adapted to be hooked into an upwardly projecting member 23 secured to a tension disk 24 slidably mounted on a post 25. The 30 tension disk 24 is normally urged downwardly by a compression spring 26 surrounding said post, the tension in the compression spring being adjusted by a suitable thumb nut 27.

A fixed tension disk or bracket 30 is suitably secured to each of the brackets 21 and against which the movable tension disk 24 is urged by the compression spring 26. The tension members 22 and the associated parts heretofore described may be of the type substantially shown in United States Patent No. 2,430,633 of November 11, 1947, and also include a member pivoted at each of the brackets 21 and having an outwardly and upwardly projecting portion 31 and inwardly and downwardly projecting hook portion or member 32.

Each of the stobs or cone holders 17 is adapted to support a suitable bobbin cone or tube of wrap yarn indicated at 35. The wrap yarn passes upwardly from each of the cones or tubes 35 and between the corresponding two tension disks 24 and 30 and through a suitable opening in the bracket 21, then through the hook member 32 and then beneath a yarn guide ring 36, only a portion of which is shown in Figure 1. The yarn guide ring 36 is suitably secured to the upper table 16. The wrap yarn W then passes upwardly through the hook on the free end of each of the corresponding levers 22 and then extends downwardly to the usual knitting instrumentalities, not shown. Each of the yarn tension levers 22 is normally urged upwardly against the tension of the yarn W by means of a tension spring 37 connected thereto and having its upper end connected to a spring anchor 38 secured on the corresponding bracket 21.

The parts heretofore described are the usual parts of a wrap stripe mechanism of a knitting machine and it is with these parts that the present invention is adapted to be associated. It is evident, however, that there are many other types of yarn tension devices and stop motion actuating mechanisms which may be mounted on the upper table 16 to perform the functions of the apparatus heretofore described, the particu-

lar apparatus described being shown by way of illustration only.

During operation of the machine, upon the wrap yarn W being severed on either side of the 5 yarn tension apparatus, of which the tension levers 22 are parts, it is evident that the member 32 will swing upwardly resulting in the outer portion 31 thereof being swung to assume substantially the horizontal position. Suitable means, not shown in the present drawings but being clearly shown in Patent Numbers 2,403,633 and 2,472,649, are usually provided which are engaged by the portion 31 of the member 32 for actuating the conventional stop motion of the machine, this stop motion being of a type such as is shown in Patent Number 2,389,688.

Also, an intermediate or auxiliary stop motion actuating means, broadly designated at 40, is provided which operates in conjunction with the present invention, this intermediate actuating means being of the type disclosed in said co-pending application. The intermediate stop motion actuating means 40 may be of the type having a housing 41 suitably secured to the platform 13, as by screws 42 and which housing has an auxiliary plunger 43 mounted for longitudinal sliding movement therein and which is normally biased to move in the direction indicated by the arrow in Figure 2.

One end of the plunger 43 has a Bowden wire 44 connected thereto which, upon movement of the spring loaded auxiliary plunger 43 in the direction indicated by the arrow in Figure 2, will move therewith for operating the conventional stop motion of the knitting machine. A spring loaded latch member 45 is pivoted at one end of the housing 41 and is normally biased against one side of the housing 41 by a leaf spring member 46. This latch member 45 operates to normally maintain the plunger 43 in inoperative position, as is clearly shown in said co-pending application.

The housing 41 has a cam 47 pivotally mounted thereon, as at 50, this cam 47 being shown as substantially rectangular in Figure 2. The cam 47 has a radially extending finger 51 thereon, the free end of which terminates in closely spaced relation to the periphery of the lower table 15. The latch member 45 also bears against the cam 47, normally causing the cam to extend outwardly in substantially right angular relation to the latch member 45.

The improved stop motion actuating mechanism comprises brackets or supports each broadly designated at 55 and each of which, for purposes of simplicity of manufacture, is shown as being formed from sheet metal. It is to be understood, however, that each of the brackets 55 may be formed of any other desired sheet material. Each of the brackets 55 comprises a planar portion 56 which is bent at one edge upwardly and then inwardly and then downwardly to form a tubular portion 57 which is opened at opposite ends thereof. The outer or front end of the tubular portion 57 is closed by an upwardly bent closure portion or tab 60 integral with the planar portion 56 of the bracket 55. This closure tab 60 extends beyond the opposite side of the tubular portion 57 relative to the planar portion 56 and is then bent inwardly or rearwardly at an angle to form a cutter blade portion 61 which is sharpened at its rear edge at 62 for a purpose to be later described.

Each of the brackets 55 is secured to the upper 75 surface of the lower table 15 of the wrap head or

attachment 14 by means of the reduced threaded portion 20 of the corresponding stub 17 penetrating the same and, also, by means of a screw 63, the outer or front surface of the bracket 55 being spaced inwardly of the periphery of the lower table 15. An enlarged portion 64 of a centrifugally operable stop motion plunger 65 is mounted for longitudinal sliding movement in the tubular portion 57 formed integral with the planar portion 56 of the bracket 55. This plunger 65 is adapted to move substantially radially of the axis of the table 15.

The plunger 65 also has a reduced outer or front end portion 66 integral therewith which slidably penetrates the upturned tab or lip portion 60 integral with the planar portion 56 of the bracket 55. A limiting arm or latch, broadly designated at 67 is also formed from sheet material, such as sheet metal, substantially in the shape of an inverted channel member having downwardly projecting ears or side portions 70 integral therewith which are pivotally mounted on opposite ends of a pivot pin 69, which also serves as a stop pin, since the pivot pin 69 penetrates the tubular portion 57 of the bracket 55 and limits inward or rearward movement of the plunger 65 toward the axis of the table 15.

The pivoted limiting arm 67 has a downwardly projecting plunger limiting or restraining tab portion 71 on the free end thereof which is normally positioned outwardly or forwardly of the upturned portion 60 of the bracket 55 and which normally limits outward movement of the plunger 65 due to centrifugal force caused by rotation of the table 15. It will be noted that the side portions or ears 70 of the arm 67 terminate short of the tab 71 so the horizontal portion of the arm 67 may normally rest upon the tubular portion 57 of the bracket 55 and these down-turned side portions 70 will not engage the upturned closure portion 60 of the bracket 55.

The upper wall or horizontal portion of the arm 67 has an upwardly bulging portion 72 formed intermediate the ends thereof which is open or slotted at opposite ends thereof and which serves to support the medial portion of a leaf spring clamping member 73, this leaf spring clamping member 73 extending beneath the upwardly bulging portion 72 and normally being held against the upper surface of the arm 67 by the upwardly bulging portion 72. The inner or rear end of the leaf spring member 73 has an enlarged portion 74 integral therewith which is provided with an opening 75 in which a second upwardly bulging portion 76 formed in the upper wall of the arm 67 is adapted to fit to thus assist in securing the leaf spring member 73 to the upper surface of the arm 67.

The manner in which the leaf spring member 73 is secured to the arm 67 permits easy removal thereof for replacement or the like.

It will be noted that the free end of the leaf spring member 73 is turned upwardly slightly or away from the arm 67, and also extends outwardly or forwardly slightly beyond the down-turned tab 71 to facilitate the ingress of a yarn tail between the leaf spring member 73 and the upper surface of the arm 67 for clamping securing the yarn tail to the arm 67. When the yarn tail is inserted between the arm 67 and the leaf spring member 73, the tail may be severed by means of the blade 61, heretofore described.

Now, upon the yarn being substantially exhausted from the associated cone or tube 35, the upward pull of the yarn W will cause the yarn clamping member or limiting arm 67 to swing

upwardly substantially from the position shown in Figure 3 to substantially the position shown in Figure 4 and, due to rotation of the table 15, centrifugal force will cause the reduced portion 66 of the plunger 65 to move outwardly to occupy substantially the position shown in Figure 4. Outward movement of the plunger 65 is limited through engagement of the enlarged portion 64 with the proximate surface of the upturned portion 60 of the bracket 55.

It is evident that, upon the reduced portion 66 of the plunger 65 being thrown outwardly by centrifugal force, it engages the finger 51 of the intermediate or auxiliary stop motion actuating device 40 to cause the same to partially rotate therewith and to, in turn, partially rotate the cam 47. This causes the cam 47 to move the latch member 45 outwardly and, of course, this will release the auxiliary plunger 43 from the latch member 45, permitting the same to move in the direction of the arrow shown in the left-hand lower portion of Figure 2. It is evident that this will cause the Bowden wire 44 to move in a like direction to actuate the conventional stop motion, not shown. This conventional stop motion may be of a type such as is shown in Patent Number 2,389,688 or Number 2,430,633. A new bobbin, cone or tube may then be placed on the stub 17 and the yarn thereon may be connected to the tail of yarn previously extending from the previous bobbin or tube and it will not be necessary to rethread the yarn.

Upon the knitting machine being stopped, in the manner heretofore described, the bobbin or cone of yarn 17 may be replaced and the corresponding plunger 65 moved inwardly so that its outer end is substantially flush with the periphery of the table 15. Also, it is necessary that the auxiliary or intermediate stop motion actuating device 40 be reset so as to condition the same for a repeat operation, as is clearly set forth in said co-pending application.

It is thus seen that I have provided an improved means for effecting operation of a conventional stop motion of a knitting machine upon the yarn from any one of the tubes or cones 17 being exhausted and which includes means for clamping holding the yarns to prevent the same from being withdrawn through the conventional tension devices, such as the tension levers 22. This, of course, saves considerable time in the replacing of empty tubes 35 with filled tubes of yarn as well as providing a simply constructed apparatus which may, consequently, be economically manufactured from a minimum of parts and does not require that any modification whatsoever be made in the knitting machine.

In the drawings and specification there has been set forth a preferred embodiment of the invention and, although specific terms are employed, they are used in a generic and descriptive sense only and not for purposes of limitation, the scope of the invention being defined in the claims.

I claim:

1. In a knitting machine having a revolving wrap stripe mechanism including a rotatable table having a plurality of circularly spaced stobs thereon for holding yarn cones filled with wrap yarn, movable yarn clamping means associated with each of said stobs for clamping the tails of yarn on said cone, a movable plunger carried by said rotatable table in association with each of said movable yarn clamping means, a plunger restraining tab integral with said yarn clamping

means and normally disposed outwardly of the outer end of each of the plungers for normally preventing outward movement of the corresponding plunger, exhaustion of the yarn from any of said cones causing movement of said corresponding movable yarn clamping means to move the plunger restraining tab away from the outer end of said corresponding plunger, said plunger being adapted to move outwardly relative to said table by centrifugal force upon the plunger restraining tab on the corresponding clamping means moving away from the outer end of the plunger, intermediate stop motion actuating mechanism disposed adjacent the revolving wrap stripe mechanism, and said plungers being adapted to actuate said intermediate stop motion actuating mechanism to stop the knitting machine upon exhaustion of yarn from any one or more of said cones.

2. In a knitting machine having a stop motion and having a rotatable wrap stripe means provided with means for holding a plurality of cones of wrap stripe yarn thereon, centrifugally operable means for effecting operation of the stop motion comprising a movable plunger disposed adjacent each of the means for holding the cones, a pivoted arm disposed adjacent each plunger, a plunger restraining tab on each of said pivoted arms normally positioned outwardly of and in engagement with the outer end of the corresponding plunger for normally limiting outward movement of the corresponding plunger, means on each pivoted arm for securing a tail of yarn from the corresponding cone of yarn thereto, whereby, upon the yarn being exhausted from any one of said cones, the tail thereof will cause the pivoted arm to swing in one direction to move the corresponding plunger restraining tab away from the outer end of the corresponding plunger, whereupon rotation of the means for holding a plurality of cones will cause said plunger to be thrown outwardly with respect thereto, and means engageable by said plunger for effecting operation of said stop motion.

3. In a circular knitting machine having a wrap stripe head including a rotary table provided with a plurality of spaced yarn cone holders thereon for holding cones of wrap yarn, said knitting machine also having a stop motion, a stop motion actuating mechanism disposed adjacent the periphery of the table, an improved stop motion control device comprising a bracket secured to the upper surface of said table adjacent each of said yarn cone holders and having a plunger mounted for movement therein, a pivoted arm pivotally connected to the bracket, means on said pivoted arm for clampingly engaging a tail of yarn from the corresponding cone, a plunger restraining element integral with the outer end of said arm normally engaging the outer end of said plunger relative to the axis of the rotary table to limit the outward movement of the plunger from said table, and actuating means on the stop motion actuating mechanism disposed immediately adjacent the periphery of said table whereby, upon the yarn being substantially exhausted from an adjacent cone, the tail thereof will be pulled upwardly to swing the pivoted arm in a like direction to cause the plunger restraining element thereon to release the plunger thereby permitting the plunger to move outwardly to engage said actuating means for the stop motion actuating mechanism for stopping the machine.

4. In a circular knitting machine having a wrap stripe head including a rotary table provided with

5 a plurality of spaced yarn cone holders thereon for holding cones of wrap yarn, said knitting machine also having a stop motion, an improved stop motion control device comprising a bracket secured to the upper surface of said table adjacent each of said yarn cone holders and having a plunger mounted for movement therein substantially radially of the axis of said table, a pivoted clamping member pivotally connected to the bracket and having means thereon for anchoring the tail of yarn from the corresponding cone thereto, a plunger restraining portion integral with said pivoted clamping member normally engaging the outer end of said plunger relative to the rotary table to limit outward movement of the plunger which may be imparted thereto by centrifugal force, intermediate stop motion actuating mechanism disposed immediately adjacent the periphery of said table and engageable by said plunger upon outward movement thereof whereby, upon the yarn being substantially exhausted from a cone, the tail thereof will be pulled upwardly to swing the pivoted clamping member in a like direction to cause the plunger restraining portion thereon to release the plunger thereby permitting centrifugal force to throw the plunger outwardly to engage said intermediate stop motion actuating means for stopping the machine.

6. In a circular knitting machine having a wrap stripe head including a rotary table provided with a plurality of spaced yarn cone holders thereon for holding cones of wrap yarn, said knitting machine also having a stop motion, an improved stop motion control device comprising a bracket secured to the upper surface of said table adjacent each of said yarn cone holders and having a plunger mounted for movement therein substantially radially of the axis of said table, a pivoted clamping member pivotally connected to the bracket and having means thereon for anchoring the tail of yarn from the corresponding cone thereto, a plunger restraining portion integral with said pivoted clamping member normally engaging the outer end of said plunger relative to the rotary table to limit outward movement of the plunger which may be imparted thereto by centrifugal force, intermediate stop motion actuating mechanism disposed immediately adjacent the periphery of said table and engageable by said plunger upon outward movement thereof whereby, upon the yarn being substantially exhausted from a cone, the tail thereof will be pulled upwardly to swing the pivoted clamping member in a like direction to cause the plunger restraining portion thereon to release the plunger thereby permitting centrifugal force to throw the plunger outwardly to engage said intermediate stop motion actuating means for stopping the machine, said bracket being provided with a rearwardly projecting blade thereon disposed immediately adjacent the plunger restraining portion on said pivoted clamping member while the pivoted clamping member is in normal position to thereby facilitate the severing of the tail of yarn as it is inserted between the pivoted clamping member and its anchoring means.

7. In a circular knitting machine having a wrap stripe head including a rotary table provided with a plurality of spaced yarn cone holders thereon for holding cones of wrap yarn, said knitting machine also having a stop motion, a stop motion actuating mechanism disposed adjacent the periphery of the table, an im-

proved stop motion control device comprising a bracket secured to the upper surface of said table adjacent each of said yarn cone holders and having a plunger mounted for movement therein, a pivoted arm pivotally connected to the bracket, means on said pivoted arm for clampingly engaging a tail of yarn from the corresponding cone, a plunger restraining element integral with the outer end of said arm normally engaging the outer end of said plunger relative to the axis of the rotary table to limit outward movement of the plunger from said table, and said bracket being provided with a rearwardly projecting blade thereon disposed immediately adjacent the plunger restraining element on said pivoted arm while the pivoted arm is in normal position to thereby facilitate the severing of the tail of yarn as it is inserted in said clamping means on said pivoted arm whereby, upon the yarn being substantially exhausted from an adjacent cone, the tail thereof will be pulled upwardly to swing the pivoted arm in a like direction to cause the plunger restraining element thereon to release the plunger thereby permitting the plunger to move outwardly to engage said stop motion actuating mechanism for stopping the machine.

7. An improved stop motion control device adapted to be associated with a knitting machine having a wrap stripe mechanism thereon including a rotatable table and wherein said table has mounted on the upper side thereof a plurality of upstanding circularly spaced stobs for holding yarn cones filled with wrap yarn, said knitting machine also having a stop motion actuating mechanism located adjacent the revolving wrap stripe mechanism and said stop motion actuating mechanism having a finger thereon positioned adjacent the periphery of said rotatable table, said improved stop motion control device comprising a bracket made from a relatively thin sheet material, such as metal, and including a planar portion adapted to be secured to the upper side of the table adjacent the periphery thereof and adjacent each of said stobs, a tubular portion formed integral with the planar portion of said bracket, said tubular portion extending radially relative to the axis of said table, said planar portion having an up-turned portion thereon closing one end of said tubular portion, a pivot pin extending transversely through said tubular portion at one end thereof, an arm made from relatively thin sheet material normally resting upon said tubular portion and having down-turned ears thereon disposed astride the pivot pin, said pivot pin penetrating said ears for pivotally connecting said arm to the tubular portion, a plunger mounted for radial sliding movement in said tubular portion, a reduced portion integral with the plunger and slidably penetrating the up-turned portion of said bracket, a down-turned tab formed integral with said arm at the outer end thereof and normally positioned outwardly of the up-turned portion of said bracket for normally limiting outward movement of the reduced portion of said plunger, and a leaf spring member secured at one end thereof to the upper surface of said arm whereby, a tail of yarn extending from the corresponding cone may be clampingly secured between the leaf spring member and the arm and, upon substantial exhaustion of the yarn from the corresponding cone, the tail of yarn will cause the arm to move upwardly, thereby moving its tab portion out

of the radial plane of the reduced portion of the plunger to permit the plunger to move outwardly to engage the finger of the stop motion actuating mechanism to stop the knitting machine.

8. In a circular knitting machine having a wrap stripe head including a rotary table provided with a plurality of spaced yarn cone holders thereon for holding cones of wrap yarn, said knitting machine also having a stop motion actuating mechanism adjacent the periphery of the table, the combination of an improved stop motion control device comprising a bracket formed from sheet metal and having a planar portion adapted to be secured to the upper surface of said table adjacent each of said yarn cone holders, said planar portion being bent or formed upwardly and then over upon itself to form a tubular portion thereon adapted to extend substantially radially of the axis of said table, a plunger mounted for longitudinal sliding movement in said tubular portion, an arm formed from sheet metal, said arm normally resting upon the upper surface of the tubular portion of said bracket, said arm having down-turned portions at opposite sides thereof, said down-turned portions straddling the tubular portion of the bracket, means pivotally connecting the down-turned portions of said arm to the bracket and serving to limit inward movement of said plunger, means in said tubular portion of the bracket limiting outward movement of the plunger, said arm having a plunger limiting tab formed on the free end thereof normally positioned outwardly of the outer end of said tubular portion relative to the axis of the table and also serving to normally limit outward movement of the plunger, which may be imparted thereto by centrifugal force, an upwardly bulging portion on said arm and being provided with slots at opposite ends thereof, a leaf spring member positioned in the upwardly bulging portion and having opposite ends thereof extending through said slots, and said upwardly bulging portion being so formed as to hold the leaf spring member against the upper surface of said arm, whereby a tail of yarn from the corresponding cone may be clamped between the leaf spring member and said arm, and, upon the yarn being substantially exhausted from the cone, the tail thereof will be pulled upwardly to move said arm in a like direction to cause the plunger limiting tab thereon to move out of the horizontal plane of the plunger, thereby permitting centrifugal force to throw the plunger outwardly to engage said stop motion actuating mechanism to stop the machine.

9. In a circular knitting machine having a wrap stripe head including a rotary table provided with a plurality of spaced yarn cone holders thereon for holding cones of wrap yarn, said knitting machine also having a stop motion actuating mechanism adjacent the periphery of the table, an improved stop motion control device comprising a bracket formed from sheet metal and having a planar portion adapted to be secured to the upper surface of said table adjacent each of said yarn cone holders, said planar portion being formed upwardly and then over upon itself to form a tubular portion thereon adapted to extend substantially radially of the axis of said table, a plunger mounted for longitudinal sliding movement in said tubular portion, an arm formed from sheet metal, said arm normally resting upon the upper surface of the tubular portion of said bracket, said arm having a down-turned portion

11

at each side thereof, said down-turned portions straddling the tubular portion of the bracket, means pivotally connecting the down-turned portions of said arm to the bracket and serving to limit inward movement of said plunger, means in said tubular portion of the bracket limiting outward movement of the plunger, said arm having a plunger limiting tab formed on the free end thereof normally positioned outwardly of the outer end of said tubular portion relative to the axis of the table and also serving to normally limit outward movement of the plunger, which may be imparted thereto by centrifugal force, a first upwardly bulging projection formed intermediate the ends of said arm, said upwardly bulging portion being provided with slots at opposite ends thereof, a leaf spring member positioned in the upwardly bulging portion and having opposite ends thereof extending through said slots, said upwardly bulging portion being so formed as to hold the leaf spring member against the upper surface of said arm, whereby a tail of yarn from the corresponding cone may be clamped between the leaf spring member and said arm and, upon the yarn being substantially exhausted from the cone, the tail thereof will be pulled upwardly to move said arm in a like direction to cause the plunger limiting tab thereon to move out of the horizontal plane of the plunger, thereby permitting centrifugal force to throw the plunger outwardly to engage said stop motion actuating mechanism to stop the machine.

10. In a circular knitting machine having a wrap stripe head including a rotary table provided with a plurality of spaced yarn cone holders thereon for holding cones of wrap yarn, said knitting machine also having a stop motion actuating mechanism adjacent the periphery of the table, the combination of an improved stop motion control device comprising a bracket formed from sheet metal and having a planar portion adapted to be secured to the upper surface of said table adjacent each of said yarn cone holders, said planar portion being bent or formed upwardly and then over upon itself to form a tubular portion thereon adapted to extend substantially radially of the axis of said table, a plunger mounted for longitudinal sliding movement in said tubular portion, said planar portion being bent upwardly at its outer end relative to the axis of the table to form a closure tab closing the axis of the table to form a closure tab closing the outer end of said tubular portion for limiting outward movement of the plunger, said plunger having a reduced portion slidably penetrating the closure tab, an arm formed from sheet metal, said arm normally resting upon the upper surface of the tubular portion of said bracket, said arm having down-turned portions at opposite sides thereof, said down-turned portions straddling the tubular portion of the bracket, means pivotally connecting the down-turned portions of said arm to the bracket, said arm having a plunger limiting tab formed on the free end thereof normally positioned outwardly of the outer end of said tubular portion relative to the axis of the table and serving to normally limit outward movement of the plunger, which may be imparted thereto by centrifugal force, an upwardly bulging portion intermediate the ends of said arm, said upwardly bulging portion being provided with slots at opposite ends thereof, a leaf spring member positioned in the upwardly bulging portion and having opposite ends thereof extending through said slots, said upwardly bulging portion being so formed as to hold the leaf spring member against the upper surface of said arm, whereby a tail of yarn from the corresponding cone may be clamped between the leaf spring member and said arm and, upon the yarn being substantially exhausted from the cone, the tail thereof will be pulled upwardly to move said arm in a like direction to cause the plunger limiting tab thereon to move out of the horizontal plane of the plunger, thereby permitting centrifugal force to throw the plunger outwardly to engage said stop motion actuating means to stop the machine, said closure

12

outward movement of the plunger, which may be imparted thereto by centrifugal force, an upwardly bulging portion intermediate the ends of said arm, said upwardly bulging portion being provided with slots at opposite ends thereof, a leaf spring member positioned in the upwardly bulging portion and having opposite ends thereof extending through said slots, and said upwardly bulging portion being so formed as to hold the leaf spring member against the upper surface of said arm, whereby a tail of yarn from the corresponding cone may be clamped between the leaf spring member and said arm and, upon the yarn being substantially exhausted from the cone, the tail thereof will be pulled upwardly to move said arm in a like direction to cause the plunger limiting tab thereon to move out of the horizontal plane of the plunger, thereby permitting centrifugal force to throw the plunger outwardly to engage said stop motion actuating means to stop the machine.

11. In a circular knitting machine having a wrap stripe head including a rotary table provided with a plurality of spaced yarn cone holders thereon for holding cones of wrap yarn, said knitting machine also having a stop motion actuating means adjacent the periphery of the table, the combination of an improved stop motion control device comprising a bracket formed from sheet metal and having a planar portion adapted to be secured to the upper surface of said table adjacent each of said yarn cone holders, said planar portion being bent or formed upwardly and then over upon itself to form a tubular portion thereon adapted to extend substantially radially of the axis of said table, a plunger mounted for longitudinal sliding movement in said tubular portion, said planar portion being bent upwardly at its outer end relative to the axis of the table to form a closure tab closing the outer end of said tubular portion for limiting outward movement of the plunger, said plunger having a reduced portion slidably penetrating the closure tab, an arm formed from sheet metal, said arm normally resting upon the upper surface of the tubular portion of said bracket, said arm having down-turned portions at opposite sides thereof, said down-turned portions straddling the tubular portion of the bracket, means pivotally connecting the down-turned portions of said arm to the bracket, said arm having a plunger limiting tab formed on the free end thereof normally positioned outwardly of the outer end of said tubular portion relative to the axis of the table and serving to normally limit outward movement of the plunger, which may be imparted thereto by centrifugal force, an upwardly bulging portion intermediate the ends of said arm, said upwardly bulging portion being provided with slots at opposite ends thereof, a leaf spring member positioned in the upwardly bulging portion and having opposite ends thereof extending through said slots, said upwardly bulging portion being so formed as to hold the leaf spring member against the upper surface of said arm, whereby a tail of yarn from the corresponding cone may be clamped between the leaf spring member and said arm and, upon the yarn being substantially exhausted from the cone, the tail thereof will be pulled upwardly to move said arm in a like direction to cause the plunger limiting tab thereon to move out of the horizontal plane of the plunger, thereby permitting centrifugal force to throw the plunger outwardly to engage said stop motion actuating means to stop the machine, said closure

13

tab extending outwardly beyond one side of the tubular portion and then being bent rearwardly to form a cutter portion, and the rear edge of the cutter portion being sharp whereby, the tail of yarn may be severed after it has been manually inserted between the leaf spring member and the arm.

12. In a knitting machine having a revolving wrap stripe mechanism including a rotatable table having a plurality of circularly spaced stobs thereon for holding yarn cones filled with wrap yarn, a pivoted arm associated with each of said stobs, a first and a second outwardly bulging projection spaced longitudinally on said arm, the first outwardly bulging projection being slotted at opposite ends thereof, a leaf spring member positioned between the first outwardly bulging projection and the pivoted arm and having opposite ends of the leaf spring member extending beyond opposite ends of the first projection, one end of said leaf spring member having an opening therein coinciding with and penetrated by the second projection to prevent longitudinal movement of the leaf spring member relative to said pivoted arm, said first outwardly bulging projection being so formed as to cause the leaf spring member to bear against the pivoted arm whereby a tail from the associated cone of yarn may be inserted between the leaf spring member and said arm for clampingly securing the same thereto, a movable plunger carried by said rotatable table in association with each of said pivoted arms, a plunger restraining tab integral with said arm and normally disposed outwardly of the outer end of each of the plungers for normally preventing outward movement of the corresponding plunger, exhaustion of the yarn from any of said cones causing movement of said corresponding movable pivoted arm to move the plunger restraining tab away from the outer end of said corresponding plunger, said plunger being adapted to move outwardly relative to said table by centrifugal force upon the plunger restraining tab on the corresponding pivoted arm moving away from the outer end of the plunger, intermediate stop motion actuating mechanism disposed adjacent the revolving wrap stripe mechanism, and said plungers being adapted to actuate said intermediate stop motion actuating mechanism to stop the knitting machine upon exhaustion of yarn from one or more of said cones.

13. In a circular knitting machine having a wrap stripe head including a rotary table pro-

14

vided with a plurality of spaced yarn cone holders thereon for holding cones of wrap yarn, said knitting machine also having a stop motion actuating mechanism adjacent the periphery of the table, the combination of an improved stop motion control device comprising a bracket formed from sheet metal and having a planar portion adapted to be secured to the upper surface of said table adjacent each of said yarn cone holders, said planar portion being bent or formed upwardly and then over upon itself to form a tubular portion thereon adapted to extend substantially radially of the axis of said table, a plunger mounted for longitudinal sliding movement in said tubular portion, an arm formed from sheet metal, said arm normally resting upon the upper surface of the tubular portion of said bracket, said arm having down-turned portions at opposite sides thereof, said 10 down-turned portions straddling the tubular portion of the bracket, means pivotally connecting the down-turned portions of said arm to the bracket and serving to limit inward movement of the plunger in said tubular portion of the bracket, said arm having a plunger limiting tab formed on the free end thereof normally positioned outwardly of the outer end of said tubular portion relative to the axis of the table and serving to normally limit outward movement of the plunger, which may be imparted thereto by centrifugal force, an upwardly bulging portion intermediate the ends of said arm, said upwardly bulging portion being provided with slots at opposite ends thereof, a leaf spring member positioned in the upwardly bulging portion and having opposite ends thereof extending through said slots, and said upwardly bulging portion being so formed as to hold the leaf spring member against the upper surface of said arm, whereby a tail of yarn from the corresponding cone may be clamped between the leaf spring member and said arm and, upon the yarn being substantially exhausted from the cone, the tail thereof will be pulled upwardly to move said arm in a like direction to cause the plunger limiting tab thereon to move out of the horizontal plane of the plunger, thereby permitting centrifugal force to throw the plunger outwardly to engage said stop motion actuating means to stop the machine.
